PULSE SYSTEM

Harold O. Peterson, Riverhead, N. Y., assignor to
 Radio Corporation of America, a corporation of
 Delaware

Application January 5, 1944, Serial No. 517,002

3 Claims. (Cl. 250—17)

1

The present invention comprises a pulse communication on-off keying system utilizing pulses which are always substantially 50% mark or weight and in which energy is radiated during only the mark intervals. I have found that a pulse system utilizing pulses of substantially 50% mark requires the narrowest receiver band width of any pulse communication system. The term "50% mark" is herein used to refer to that condition where the mark pulses have the same duration as the space intervals.

The following is a detailed description of the invention accompanied by a drawing, wherein:

Fig. 1 diagrammatically illustrates a transmitter for producing pulses of 50% mark in accordance with the invention;

Fig. 2 diagrammatically illustrates a receiver for use in connection with the transmitter of Fig. 1;

Figs. 3, 4 and 5 illustrate the wave forms to be found in certain connections of the receiver of Fig. 2; and

Fig. 6 graphically illustrates the effect that pulses of different mark or weight have on the output amplitude of the receiver.

Referring to Fig. 1 in more detail, there is shown a transmitter for always obtaining pulses of substantially 50% mark. This transmitter comprises a reactance tube 10 for varying the frequency of an oscillator 11, in accordance with signal modulations from a microphone 13, by way of example. The oscillator 11 may generate, by way of example, oscillations of 100 kilocycles. The output of oscillator 11 is coupled to a frequency converter 14 where the oscillations beat with oscillations from a heterodyne oscillator 15 to produce lower frequency waves in the output of the converter. The beating oscillator 15 may generate oscillations of about 110 kilocycles. Thus, the output of the converter 14 which is impressed upon the square wave generator 16 will be a variable frequency sinusoidal wave of about ten kilocycles. This ten kilocycle wave, which varies in frequency in dependence upon the signal modulation, causes the square wave generator 16 to produce square wave pulses of substantially 50% mark. The square wave generator may be of the flip-flop variety. Alternatively, if desired, the output of the converter 14 can be impressed upon a limiting amplifier in order to obtain a square wave which is 50% mark. One such limiting amplifier which can be used is described in Crosby United States Patent 2,276,565, granted March 17, 1942. These square wave pulses are impressed upon the input of a radio frequency

2

generator 17 to cause the generator 17 to produce correspondingly spaced pulses of radio frequency energy which are then passed on to an antenna 18 where the radio frequency waves are radiated to a distant receiver. The mark pulses are separated by space intervals during which no energy is radiated. In practicing the invention, the pulse rate should always be greater than twice the highest modulating frequency.

Fig. 2 shows a receiving system for receiving the 50% mark pulses transmitted by the system of Fig. 1. This receiver comprises an antenna 19 which feeds a radio frequency amplifier 20, the latter in turn supplying the amplified pulses to a frequency converter 21, where the radio frequency energy is beat with the oscillations from a local oscillator 22 to produce pulses of intermediate frequency energy. The intermediate frequency energy from the output of the frequency converter 21 is supplied to an intermediate frequency amplifier 23 which in turn feeds the pulses to a rectifier 24. Both the intermediate frequency amplifier 23 and the radio frequency amplifier 20 comprise suitable selectivity and gain circuits. The output of the rectifier 24 consists of unidirectional pulses which are optionally amplified at 25 and then passed on to a clipper 26. The rectified or unidirectional pulses supplied to the clipper are of substantially 50% mark and contain noise ripples. The wave form of these rectified pulses is shown in Fig. 3. The clipper 26 removes a portion of the rectified pulse between the top and bottom to provide a clean pulse having the noise ripples removed. This portion of the pulse removed from the unidirectional pulse appears between the two horizontal lines labeled "Clipper Levels." It will thus be seen that the clipper is a top and bottom limiter which removes noise and variations above and below certain limits. Putting it in other words, the clipper removes the noise from the flat tops of the direct current pulses and also the noise from the spaces between the pulses. The clipped pulses from the output of 26 may have the wave form of Fig. 4. It will be seen that the amplitudes of the clipped pulses are constant although the lengths of the pulses and the phase may have variations caused by noise. The bi-directional arrows on the starting and trailing edges of the pulses of Fig. 4 are intended to designate variations in length and phase caused by noise.

The output of the clipper is fed into a band pass filter 27 which is designed to pass the mean pulse frequency plus and minus sideband frequencies produced by the signal modulation.

The output of the band pass filter will have a wave form, as shown substantially by Fig. 5. The carrier in the output of filter 27 will have a variable frequency and can then be supplied to a suitable frequency modulation discriminator and detector circuit 28, where the variable frequency is converted to amplitude modulations. The resultant amplitude modulated wave can then be fed to an audio frequency amplifier 29 whose output is coupled to a suitable acoustic transducer 30. This acoustic transducer is shown to be a pair of headphones, although it will be understood that it can be a loudspeaker or any suitable recording device.

Although it has been shown that noise has the effect of varying the percent mark of the received pulses, particularly as they come out of the clipper, these variations in the percent mark at values near 50% have little or no effect on the output amplitude. This is illustrated in Fig. 6, which graphically shows the amplitude of the wave in the output of the band pass filter 27 replotted as current output on the ordinate scale and percent mark on the abscissa scale. The system thus enables one to obtain a very large gain in signal to noise ratio, provided the pulse amplitude is above the threshold value of about twice the peak noise voltage. Also, by means of experiments, I have found that pulses of 50% mark require the narrowest receiver band width of any pulse system.

The present invention is designed particularly for use in an "on-off" keying system, in which energy is radiated during the "on" or mark intervals and no energy is radiated during the "off" or space intervals.

What is claimed is:

1. The method of operating a transmitter in a pulse communication system which comprises varying the frequency of an oscillator in accordance with signal modulations, beating said frequency with constant frequency oscillations to produce a lower varying frequency, controlling a square wave generator by said lower varying frequency to produce spaced pulses each of which has substantially the same duration as the inter-

vals between them, and generating pulses of radio frequency energy under control of said aforementioned spaced pulses.

2. A pulse transmitter for sending spaced pulses each of which has substantially the same duration as the intervals between them, comprising an oscillation generator, a reactance tube modulator coupled to said oscillator for varying the frequency or phase of the oscillations from said oscillator in accordance with signal modulations, a frequency converter, a constant frequency oscillator generating oscillations different than said first oscillator, connections from both oscillators to said converter to thereby produce a variable beat frequency of lower frequency, a square wave generator coupled to the output of said converter and producing spaced pulses whose durations are always substantially equal to the intervals between the pulses, and a radio frequency oscillator under control of the output of said square wave generator.

3. The method of communication which comprises producing spaced pulses whose durations are always substantially equal to the intervals between them, at a rate greater than twice the highest modulation frequency, and varying the occurrence time of said pulses in accordance with signal modulations without substantially varying the durations of said spaced pulses.
